UNITED STATES PATENT OFFICE.

HENRY J. FOURTNER, OF HAZLETON, IOWA.

BAND-CUTTER AND FEEDER.

SPECIFICATION forming part of Letters Patent No. 716,022, dated December 16, 1902.

Application filed November 25, 1901. Serial No. 83,548. (No model.)

To all whom it may concern:

Be it known that I, HENRY J. FOURTNER, a citizen of the United States, and a resident of Hazleton, in the county of Buchanan and 5 State of Iowa, have invented a new and Improved Band-Cutter and Feeder, of which the following is a full, clear, and exact description.

The invention relates to threshing-machines, and more particularly to band-cutters and feeders thereof, and preferably to such as are shown and described in the Letters Patent of the United States, No. 594,784, granted to me November 30, 1897.

15 The object of the invention is to provide a new and improved band-cutter and feeder arranged to properly cut the bands of the sheaves, to spread the same after the band is cut, and to feed the grain to the drum of the 20 threshing-machine in quantities corresponding to the capacity of the drum to prevent overfeeding and consequent bad threshing of the grain.

25 The invention consists of novel features and parts and combinations of the same, as will be fully described hereinafter and then pointed out in the claims.

30 A practical embodiment of my invention is represented in the accompanying drawings, forming a part of this specification, in which similar characters of reference indicate corresponding parts in all the figures.

35 Figure 1 is a side elevation of the improvement as applied. Fig. 2 is a rear side elevation of the same. Fig. 3 is a longitudinal sectional elevation of the same. Fig. 4 is a plan view of the shaking conveyer. Fig. 5 is a plan view of the cutter, spreader, feeder, and the drum of the threshing-machine. Fig. 6 40 is an enlarged side elevation of the fastening device for the cutter-knives. Fig. 7 is an enlarged cross-section of one of the cylinders for carrying the knives or hooks, the section being taken on the line 77 of Fig. 8; and Fig. 45 8 is a longitudinal sectional elevation of the same.

The improved band-cutter and feeder in its general construction comprises a feeder A for conveying the sheaves to the revolute cutter 50 B, which serves to cut the bands of the sheaves, the cutter operating in conjunction and in unison with a revolute spreader C for

spreading the grain after the bands are cut, the sheaves then being fed by a revolute feeder D to the drum E of the threshing-machine, the loose chaff and straw that may drop from the inner end of the conveyer A and from the feeder D being fed to the bottom of the drum E by a shaking conveyer F. The parts of the band-cutter and feeder are mounted on a framework G, which may be part of the threshing-machine, as indicated in the drawings.

The conveyer A is in the form of a belt of any suitable construction and is arranged with an outer upwardly and inwardly inclined leg A' and a shorter inner leg A'', inclined downwardly and inwardly, the outer leg A' carrying the sheaves to the knives B' of the cutter B, located at the apex of the conveyer A. The shorter inner leg A'' of the conveyer extends under the spreader C, and its lower inner end discharges the chaff and loose straw onto the shaking conveyer F.

The knives B' of the cutter B extend from the peripheral surface of a cylinder B'', and said knives are curved and arranged in spiral rows starting from near the middle of the cylinder and running to the ends thereof, as indicated in Fig. 5. The spreader C is provided with curved hooks C', extending from the peripheral surface of a cylinder C'', and said hooks C' are likewise arranged in spiral rows extending from one hook, which is common to both rows and located at the middle of the cylinder outwardly to the ends thereof, but in such a manner that the hooks C' pass corresponding knives B' of the cutter B when the machine is in operation. As indicated in Fig. 5, the knives in the two spiral rows are arranged in pairs, and the knives in one row have a sharper curve than the knives in the other row, as will be understood by reference to Figs. 1 and 2.

The hooks D' of the feeder D project from the peripheral surface of a cylinder D'' and are arranged in transverse rows, with the hooks standing close together but arranged in such a manner relative to the hooks C' that the hooks C' and D' readily pass each other when the machine is in operation. The hooks D' are curved, but comparatively shorter than the hooks B' and C', as indicated in Figs. 1 and 2.

The cutter B, as previously mentioned, rotates in unison with the spreader C, and the cylinders are so arranged that the middle hook of the spreader C passes between the two innermost knives of the cutter B and the pairs of following hooks and knives correspondingly pass each other for the hooks to cut the band and to operate in unison with the hooks C' to properly spread the sheaves after the bands are cut. The knives B' in each pair are given different curvatures to prevent a sheaf from passing the cutter B without the band being cut, it being evident that the knives act on the sheaves one in advance of the other to strike at different points on the sheaves to positively cut the band.

The band-cutter B is driven from the drum E of the threshing-machine, and for this purpose the shaft B³ of the cutter is provided at one end with a pulley H, over which passes a belt H', also passing over a pulley H², secured on the shaft E' of the drum E. Thus when the threshing-machine is set in motion a rotary motion is transmitted from the drum E to the cutter B to rotate the latter at a considerably lower rate of speed than the drum E. As previously mentioned, the shaft B³ and the spreader C rotate in unison, and for this purpose the shaft B³ is provided with a sprocket - wheel I, over which passes a sprocket-chain I', also passing over a sprocket-wheel I², secured on the shaft C³ of the spreader C, the sprocket-wheels I and I² being of the same diameter. The feeder D is rotated at a higher rate of speed than the cutter B and spreader C, and said feeder is driven from the shaft B³, and for this purpose the shaft B³ is provided with a sprocket-wheel J, over which passes a sprocket-chain J', also passing over a sprocket-wheel J², secured to the shaft D³ of the spreader D, the sprocket-wheel J² being larger in diameter than the sprocket - wheel J. A tightening sprocket-wheel J³ (see Fig. 2) engages one run of the sprocket-chain J' to give the desired tension to the latter.

The conveyer A is driven from the cutter B, and for this purpose the shaft B³ thereof is provided with a pulley K, connected by a bolt K' with a pulley K², held on the shaft L, carrying driving-wheels L' for imparting a traveling motion to the conveyer-belt, as will be readily understood by reference to Fig. 3, said conveyer-belt passing over sprocket-wheels A³, A⁴, and A⁵, journaled in suitable bearings on the frame G, the lower run of said conveyer-belt also passing over a sprocket-wheel A⁶, located near the sprocket-wheel A⁴. A belt-tightener K³ is provided for the belt K', and the pulley K² is provided with a friction-governor of any approved construction, so as to govern the speed of the conveyer-belt A and prevent overfeeding of the sheaves to the cutter B.

65 The shaking conveyer F operates in conjunction with the conveyer A, and for this purpose the shaft A⁷ of the sprocket-wheel A⁵

carries a sprocket-wheel O, over which passes a sprocket - chain O', also passing over a sprocket-wheel O², attached to a crank-shaft 70 P, journaled in suitable bearings on the frame G. Said shaft P is provided with crank-arms P', (see Fig. 4,) engaging bearings F' on the shaking conveyer F, which latter is in the shape of a table hung at its outer end on said 75 crank-arms and resting at its free inner end on the bottom leading to the threshing-drum E. The table F is provided on its top surface with the usual notched longitudinally-extending bars F², so that when the material 80 falls upon the shaking conveyer and the latter receives a forward-and-backward shaking motion then said material is fed inwardly and finally passes upon the bottom to the drum E to be threshed.

The cylinders B², C², and D² are preferably alike in general construction, as illustrated in Figs. 7 and 8—that is, each cylinder is provided with solid cylinder-heads B⁴, on which are secured the transverse bars B⁶, supporting keepers B⁷ for receiving and carrying the knives and hooks B', C', and D'.

Having thus fully described my invention, I claim as new and desire to secure by Letters Patent—

1. A band-cutter and a feeder for threshing-machines, comprising a revoluble cutter having curved cutting-knives, a revoluble spreader adjacent to said cutter and having curved hooks, the knives of the cutter and the hooks of the spreader being arranged in spiral rows extending from the middle of the cutter and spreader to the ends thereof the knives of each row having different curvatures, the knives and hooks operating in conjunction with each other for spreading the grain after the knives have cut the bands of the sheaves, and a revoluble feeder rotating at a higher rate of speed than the cutter and spreader, said feeder having short curved hooks arranged in transverse rows, the hooks in a row standing close together and the hooks serving to take the sheaves from the spreader-hooks and to lift the butts of the sheaves and feed the latter to the drum of the threshing-machine, as set forth.

2. A band-cutter and feeder for threshing-machines, comprising a conveyer extending in A shape, a revoluble cutter located over said conveyer at or near the apex thereof and arranged for cutting the bands of the sheaves and for turning the sheaves straight, the knives of the cutter being arranged in spiral rows, the knives of each row having different curvatures, a revoluble spreader adjacent to said cutter and extending over the inner leg of said conveyer, said spreader operating in conjunction and unison with the cutter to spread the sheaves after the bands are cut by the cutter, a revoluble feeder between said spreader and the threshing-machine drum, the feeder serving to receive the sheaf and feed the same from the spreader and to lift the butt of the sheaf to the drum, means for positively rotat-

ing said cutter, spreader and feeder, a driving device for driving said conveyer and connected with said means, and a friction-governor for said driving device, as set forth.

- 5 3. A band-cutter and feeder for threshing-machines, comprising a conveyer extending in A shape, a revoluble cutter located over said conveyer at or near the apex thereof and arranged for cutting the bands of the sheaves 10 and for turning the sheaves straight, the knives of the cutter being curved and arranged in spiral rows, the knives of each row having different curvatures, a revoluble spreader adjacent to said cutter and extending 15 over the inner leg of said conveyer, said spreader operating in conjunction and unison with the cutter, a revoluble feeder between said spreader and the threshing-machine drum, the feeder serving to receive the sheaf 20 and feed the same from the spreader and to lift the butt of the sheaf to the drum, an auxiliary shaking conveyer for conveying any chaff and loose straw that drops from said feeder and the inner leg of the conveyer to 25 the bottom of the drum, means for positively rotating said cutter, spreader and feeder, a driving device for driving said conveyer and connected with said means, a friction-governor for said driving device, and a shaking 30 mechanism driven from said driving device for imparting a shaking motion to said auxiliary conveyer, as set forth.

4. A band-cutter and feeder for threshing-machines, provided with a revoluble band-cutter having a cylinder and knives arranged 35 in spiral rows on the periphery of the cylinder, the rows starting from near the middle of the cylinder and extending to the ends thereof, and the knives being arranged in pairs, the knives of each pair having different 40 curvatures.

5. A band-cutter and feeder for threshing-machines, provided with a revoluble band-cutter having a cylinder and knives arranged 45 in spiral rows on the periphery of the cylinder, the rows starting from near the middle of the cylinder and extending to the ends thereof and the knives being arranged in pairs, the knives of each pair having different 50 curvatures, and a revoluble spreader operating in conjunction and in unison with said cutter, and comprising a cylinder and curved hooks thereon, the hooks being arranged in spiral rows, each row having a hook common to both rows and located at the middle of the 55 cylinder, the rows running from this common hook to the ends of the cylinder, as set forth.

In testimony whereof I have signed my name to this specification in the presence of two subscribing witnesses.

HENRY J. FOURTNER.
